UNITED STATES PATENT OFFICE

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE

BACK BOX PLATE FOR LOOMS

Application filed September 17, 1931. Serial No. 563,372.

This invention relates to looms and more particularly to means for aligning the back box plate with the reed to form a proper guiding surface for the shuttle in its flight.

5 Looms as commonly constructed include a wooden lay supported on cast iron swords and carrying a reed, and at either end a shuttle box. The box consists of a front binder plate and a back guiding plate, having an over- 10 hanging surface or guard to prevent the shuttle from rising in its flight. This back box plate is customarily formed of cast iron and is secured at its outer end to the end of the lay, and at its inner end to an extension on 15 the adjacent sword.

Difficulty has been experienced in aligning the shuttle guiding surface of this back box plate with the front surface of the reed.

20 The wooden lay end may twist or warp, and the cast iron box plates frequently become warped while being formed.

25 Heretofore it has been proposed to provide means for warping and twisting the back box plate to partially align its surface with the reed. This construction is objectionable, in that, the twisting imposes a strain upon the the cast iron and the impact of the shuttle on entering the shuttle box frequently causes the strained cast iron to snap. I propose to 30 overcome this difficulty by providing means whereby the shuttle guiding surface of the back box plate may be accurately aligned with the surface of the reed without subjecting the plate to objectionable stresses.

35 It is accordingly an object of my invention to provide means for universally adjusting the shuttle guiding surface of the back box plate of a loom.

40 A further object of my invention is to provide, in a loom embodying a lay carried reed and shuttle boxes, a back box plate formed of an attaching portion adapted to be fixed to the lay end and a shuttle guiding portion connected to the attaching portion 45 by means which permit of a universal adjustment.

As illustrative of the preferred embodiment of my invention, reference is made to the drawings in which:

50 Fig. 1 is a fragmentary plan view of the

right hand end of the lay of a loom, and showing a construction embodying my invention.

Fig. 2 is a vertical cross sectional view taken on line 2—2 of Fig. 3, and

Fig. 3 is a cross sectional view taken on line 3—3 of Fig. 1.

The lay 1 is supported, as is usual, by swords 2 for reciprocating movement toward and from the front of the loom. The lay 60 carries a reed (not shown) and also carries at either end a shuttle box indicated generally at 3. The shuttle 4 is alternately picked from side to side of the loom by picker sticks 5 carrying the picker 6. The front member 65 7 of the shuttle box is a binder for frictionally urging the shuttle against the rear wall for checking the shuttle at the end of its flight. The back box plate 8 serves primarily to provide a guiding surface to insure the 70 straight flight of the shuttle through the shed. To this end the guiding surface must be carefully aligned with respect to the reed which also serves as a guiding surface for the shuttle while the latter is in the shed.

I have formed this back box plate of two parts or pieces, the outer one 9 of which is attached as at 10 to the lay end. The inner part of the back box plate is provided with a vertical shuttle guiding surface or wall 11 80 and an overhanging guiding surface 12. The two pieces are connected by a universal joint herein shown as consisting of a projection 13 on the outer piece 9 cooperating with a depression 14 formed in the inner piece 15. 85 The projection has a surface which is a segment of a sphere, and I have shown the depression as having a similarly shaped surface, although this latter is not necessary. Obviously, the depression may have other 90 shapes than that shown and still cooperate properly with the surface of the projection.

A clamping means is provided for securing the two pieces together; the clamping means consisting in the present instance of a bolt 16 passing through an enlarged opening 17 in the outer piece and threadedly engaging the inner piece. This bolt passes through the projection 13 radially of the 95 surface thereof.

It will thus be seen that by loosening this clamping bolt, the inner piece which carries the shuttle guiding surface 11 may be pivoted about the bolt, which normally extends approximately horizontally, or may be pivoted about a vertical axis at right angles to the bolt, or may be twisted about an axis extending longitudinally of the lay. This connection provides in substance a universal joint. The inner end of the box plate is attached to an extension 18 on the sword as is usual.

In order to provide a rigid connection between the extension 18 and the box plate the contiguous surfaces thereof should be fitted and positioned in the same plane. To this end I have provided the back surface of the inner end of the box plate with spaced filing lugs 19, which after adjustment of the universal joint may be fitted to the extension 18 of the sword. Obviously, a rigid union between the box plate and the sword may be provided in other ways.

It is to be understood that the embodiment of my invention herein illustrated and described is for purposes of illustration only, and not of limitation, as the construction disclosed may be departed from in many respects without departing from the spirit of my invention.

I claim:

1. A two piece back box plate for looms, said pieces connected by a universal joint.
2. A two piece back box plate for looms, said pieces being provided, respectively, with a projection having a surface which is a segment of a sphere and a cooperating depression forming a universal joint between said pieces.
3. A two piece back box plate for looms, said pieces provided, respectively, with a projection having a surface which is a segment of a sphere and a cooperating depression, and releasable means for clamping said pieces together, whereby they may be universally adjusted relative to each other.
4. A two piece back box plate for looms, said pieces provided, respectively, with a projection having a surface which is a segment of a sphere and a cooperating depression, and a clamping bolt passing loosely through one of said pieces radially of said spherical surface, whereby the pieces may be universally adjusted relative to each other and clamped in adjusted position.
5. A back box plate for looms comprising a shuttle guiding part and a part adapted to be fixed to a lay end, said parts being universally adjustable relative to each other.
6. A back box plate for looms comprising a shuttle guiding part and a part adapted to be fixed to a lay end, said parts being provided, respectively, with a projection having a surface which is a segment of a sphere and

a cooperating depression, providing a universal joint between said parts.

7. A back box plate for looms comprising a shuttle guiding part adapted to be aligned with a reed, an attaching part adapted to be fixed to a lay end, hinge means providing a universal adjustment between said parts to permit proper alignment of the shuttle guiding part with the reed and means for clamping said parts in adjusted relation.

8. In a loom, the combination of a lay adapted to carry a reed, with a shuttle box carried on said lay, said shuttle box including a universally jointed back box plate fixed at each end with respect to the lay, and means for clamping the parts of said joint together; whereby the shuttle guiding surface of the box plate may be adjusted relative to the reed and clamped in adjusted position.

9. In a loom, the combination of a sword supported lay adapted to carry a reed, with a shuttle box carried on the lay, said shuttle box including a back box plate fixed at its outer end to the lay end and at its inner end to the adjacent sword, said box plate provided intermediate its ends with a universal joint and being further provided at its inner end with filing lugs adapted to be fitted to the surface of the sword; whereby the shuttle guiding surface of the box plate may be aligned with the surface of the reed.

10. In a loom, the combination of a sword supported lay adapted to carry a reed, with a shuttle box carried on the lay, said shuttle box including a back box plate having a universally adjustable shuttle guiding surface, and clamping means for retaining said surface in adjusted position, whereby the said shuttle guiding surface may be accurately positioned relative to the surface of the reed.

11. A two piece back box plate for looms, said pieces pivoted together in such a manner as to permit adjustment of the inner end of the plate about both a vertical and a horizontal axis passing transversely through the plate.

12. A back box plate for looms comprising a shuttle guiding part and a part adapted to be fixed to a lay end, said parts pivoted together by means of a joint which will permit adjustment of the shuttle guiding part about angularly related axes passing transversely through the plate.

13. A back box plate for looms formed of at least two pieces, one of said pieces being provided with a convex projection and the other piece being provided with a depression cooperating with said projection to form a universal joint.
